DISPATCHING AND SCHEDULING SYSTEM

Charles Harvey Levy, Jr., Maplewood, N. J., assignor to Otis Elevator Company, New York, N. Y., a corporation of New Jersey

Application May 25, 1935, Serial No. 23,368

15 Claims. (Cl. 177—336)

The invention relates to dispatching and scheduling systems and especially to such systems as applied to a plurality of elevator cars arranged in a group.

In the operation of a plurality of elevator cars arranged in a group, it is desirable, particularly in certain types of installations, that some supervisory control be exercised over them in order that efficient and satisfactory service may be obtained. Such supervisory control may be effected manually or by means of mechanism automatically operated and controlled. The present invention relates to the exercise of supervisory control over a group of elevators through the medium of such mechanism.

The main feature of the invention is the provision of a supervisory control over a plurality of elevator cars such that the cars are dispatched from a dispatching floor always in accordance with the order in which they approach or arrive at such floor.

Another feature of the invention resides in the giving of a notification signal to indicate which car is to be the next to leave a dispatching floor, with such signals given in the order of arrival of the cars at that floor, regardless of their order of arrival.

Another feature is to indicate when a car is to leave a dispatching floor by giving a start or dispatch signal for that car, with such signals given in the order of arrival of the cars at that floor, regardless of their order of arrival.

Other features and advantages will become apparent from the following description and appended claims.

The invention will be described as applied to a system of supervisory control for elevators in which visual signals are employed to indicate which car is to be the next to leave the dispatching floor and when the car which is selected to be the next to leave should depart. The notification or warning signals are given only to cars at the dispatching floor and only to one car at a time. A start or dispatch signal is given in response to the operation of mechanism which normally operates at regular intervals of time. Provision is made so that if there is no car at a dispatching floor eligible to be dispatched at the time that a car normally is to receive a dispatch signal, the giving of the signal is delayed until a car arrives at the dispatching floor. In the event that no car arrives at the dispatching floor by the time a given percentage of the time interval has elapsed, operation of the mechanism for giving the dispatch signals is suspended until a car

leaves the dispatching floor. Such operation is preferably had both at a lower and upper terminal floor as dispatching floors.

In applying the invention to such supervisory control system, both the notification and the dispatch signals are given to only one car at a time. The cars are selected to receive these starting signals in the order in which they arrived at the dispatching floor regardless of their order of arrival. When a car is selected to be the next to receive a starting signal, the notification signal for that car is given. When the selected car receives its starting signal and leaves, the system becomes effective incident to the starting of the previously selected car from the dispatching floor to select another car to receive its starting signal. Regardless of the number of cars which may be at the dispatching floor at the time such selection is made, the cars are selected in the order in which they arrived at the dispatching floor.

In the drawings:—

Figure 1 is a schematic diagram of a four car elevator bank illustrating one relative position of the cars thereof;

Figures 2 and 3, taken together, constitute a wiring diagram of a dispatching and scheduling system in accordance with the invention;

Figure 4 is an elevation of a control panel diagrammatically illustrating all the electromagnetic switches, together with the timing motor and related equipment, employed in the diagram of Figures 2 and 3;

Figure 5 is a view along the line 5—5 of Figure 4, showing details of certain of the relays;

Figure 6 is a view similar to Figure 5, but illustrating the positions of the parts when the actuating coils of the relays are energized;

Figure 7 illustrates in detail one of the floor selector brushes that is schematically shown in the wiring diagram, and also illustrates in detail a floor selector contact with which the floor selector brush is in engagement;

Figure 8 is a view of the floor selector brush taken along the line 8—8 of Figure 7;

Figure 9 illustrates in detail a direction-distinguishing floor selector switch that is schematically shown in the wiring diagram;

Figure 10 is a view of the direction-distinguishing floor selector switch taken along the line 10—10 of Figure 9; and

Figure 11 is a section of a portion of the timing equipment, taken along the line 11—11 of Figure 4.

Referring to Figure 1, there is shown a bank

of four elevator cars, cars Nos. 1, 2, 3, and 4, operating between two dispatch floors 11 and 12. These dispatch floors are normally, though not necessarily, the first floor and the top floor. The figure illustrates the position and direction of travel of four cars at one instant in the cycle of events as a convenient starting point for the descriptions of the dispatching and scheduling systems that follow.

10 There is provided in each car a suitable control panel on which are mounted the various control switches and signals for that car. For simplicity, Figure 1 illustrates the control panel for each car as mounting only operators' control switches 13 1—35, 2—35, 3—35, and 4—35 for cars Nos. 1, 2, 3, and 4 respectively; up warning lights 1—54, 2—54, 3—54 and 4—54 for cars Nos. 1, 2, 3, and 4 respectively; up start lights 1—137, 2—137, 3—137 and 4—137 for cars Nos. 1, 2, 3, and 4 respectively; down warning lights 1—44, 2—44, 3—44, and 4—44 for cars Nos. 1, 2, 3, and 4 respectively; and down start lights 1—111, 2—111, 3—111, and 4—111 for cars Nos. 1, 2, 3, and 4 respectively.

20 Suitably positioned so as to be convenient of access for the starter or other official is a dispatch panel 13 upon which are mounted various hand operated switches and certain other apparatus to control the operation of the dispatching and scheduling system. As illustrated, these 30 include the knife switches 1—50, 1—125, 2—50, 2—125, 3—50, 3—125, 4—50, 4—125, 85, 20, 24, 22, 26, 88 and 101, and the speed control switch 52, all of which are referred to later in more 35 detail. Also mounted upon the dispatch panel 13 or elsewhere so as to be readily visible to the starter or other official is a set of signal lights 1—55, 2—55, 3—55, and 4—55 for cars Nos. 1, 2, 3, and 4 respectively, at the lower dispatch floor, a set of signal lights 1—45, 2—45, 3—45, and 4—45 for cars Nos. 1, 2, 3, and 4 respectively, at the upper dispatch floor, and a set of starters' signal lights 127 and 126 for the lower and upper dispatch floors respectively.

40 Suitably positioned so as to be visible to intending passengers in the hall at the lower dispatch floor—preferably over the entranceways to the corresponding cars—are the up hall lights 1—53, 2—53, 3—53, and 4—53. In a similar manner, down hall lights 1—43, 2—43, 3—43, and 4—43 are provided in the hall at the upper dispatch floor.

45 Figures 2 and 3 show a diagram of circuit connections for dispatching and scheduling the four 55 car bank of Figure 1 in accordance with the invention. In this diagram no attempt is made to show the coils and contacts of the various electromagnetic switches in their associated positions, a "straight" diagram being employed 60 wherein the coils and contacts of the various switches are separated in such a manner as to render the circuits involved relatively simple. The electromagnetic switches have been given letters in addition to the usual reference numbers, so that although the parts of the switches 65 have been separated for simplicity in showing the circuits, they may still be identified by means of the common letters. To aid in understanding the diagram, switches, coils, contacts and other 70 apparatus that correspond for each car have been similarly designated, with the exception of prefixes 1—, 2—, 3—, and 4— to designate the car with which the part is employed. Also, to facilitate the ready location in the wiring diagram of 75 any element referred to in the description, the

reference numbers employed are in numerical sequence (neglecting car identifying prefixes) in that the lowest number (20) referred to in the diagram is at the upper left hand corner of Figure 2, with succeeding numbers following in numerical sequence (as near as practicable) left to right downwardly of the sheet on which Figure 2 appears, and then left to right downwardly of the sheet on which Figure 3 appears. The various elements of the diagram are shown in the 10 positions they occupy when the cars are in the relative positions illustrated in Figure 1, when all knife switches are open, and when all the circuits are disconnected from the power mains. The electromagnetic switches thus are shown in 15 their deenergized positions, so that the contacts thereof that are shown as separated are forward contacts and the contacts that are shown as engaged are back contacts.

The designations of the electromagnetic 20 switches are as follows:

A	Up car holding relay	25
AA	Up car releasing relay	
B	Down car holding relay	
BB	Down car releasing relay	
K	Timing motor relay	
S	Car starting switch	
Y	Auxiliary up car holding relay	
Z	Auxiliary down car holding relay	30
U	Up schedule relay	
D	Down schedule relay	
UU	Up dispatching relay	
DD	Down dispatching relay	
SU	Selective up light relay	35
SD	Selective down light relay	

In the diagram of Figures 2 and 3, the relays termed the "selective up light relays" (SU) and the "selective down light relays" (SD) are of novel construction, and preferably are as illustrated in Figure 4. The selective up light relays (SU), one for each car, and associated with events at the lower dispatch floor, are arranged radially about a common center post 206. The selective down light relays (SD), one for each car, and associated with events at the upper dispatch floor, are arranged radially about a common center post 208. The selective up light relays and the selective down light relays are 40 similar in construction and operation, so only the selective up light relays are described in detail. In this description, reference is also made to Figures 5 and 6, which show further details of selective up light relays 1—SU, 2—SU, and 3—SU.

45 Selective up light relay 1—SU for car No. 1 has 55 its actuating coil 1—SU216 mounted in a U-shaped frame 1—SU218 of magnetic material that is suitably secured along its yoke to the vertical control panel 206. At one of the ends of the frame 60 is pivotally mounted, as at 1—SU211, an armature arm 1—SU212, preferably of magnetic material, to which is preferably secured a core 1—SU213 of magnetic material, arranged for movement in and out of a hollow core at the end of the actuating coil. A rearward extension of armature arm 1—SU212 is subjected to the action of an armature arm spring 1—SU214 for urging the armature arm to its outward position, as shown in Figures 4 and 5. The armature arm spring is illustrated 65 as a coil spring positioned about a spring rod 1—SU215 stationarily secured to frame 1—SU218, and projecting through a suitable elongated aperture in the rearward extension of armature arm 1—SU212, the spring being positioned between the armature arm extension and a compression- 70

75

adjusting nut and washer at the free end of the rod. The outward rotation of armature arm 1—SU212 is limited by the engagement of the armature arm extension with a stop in the form of a rubber washer 1—SU216 positioned on rod 1—SU215 between the armature arm extension and the frame.

To another extension of armature arm 1—SU212 is pivotally mounted, as at 1—SU217, a contact arm 1—SU220, preferably of light material such as aluminum. A rearward extension of this contact arm is subjected to the action of a contact arm spring 1—SU221 for urging the contact arm to its outward position, as shown in Figures 4 and 5. The contact arm spring is illustrated as a coil spring positioned about a spring rod movably secured to armature arm 1—SU212 and projecting through a suitable aperture in the rearward extension of contact arm 1—SU220, the spring being positioned between the contact arm extension and a pin-secured washer at the free end of the rod. Adjustment of the compression of contact arm spring 1—SU221 is obtained by providing, for the washer-securing pin, a plurality of holes in spring rod 1—SU222. The outward rotation of contact arm 1—SU220 is limited by the engagement of a shoulder on the rearward extension of the contact arm with the armature arm, as illustrated in Figure 4.

30 Mounted on contact arm 1—SU220 is a contact block 1—SU223 of insulating material upon which are mounted two contact blades, one at each side of contact arm 1—SU220. One contact blade is the movable contact element of contacts 1—SU138, while the other contact blade is the movable contact element of contacts 1—SU56. The other contact elements of contacts 1—SU138 and 1—SU56 are two contact studs mounted on an insulating block 1—SU224 fastened to frame 40 1—SU210 by means of a bracket 1—SU225. The contact blades of contacts 1—SU138 and 1—SU56 engage with the contact studs of their respective contacts when armature arm 1—SU212 and contact arm 1—SU220 are each in their innermost 45 positions, as illustrated for relay 1—SU in Figure 6. The contact blades are preferably secured to contact block 1—SU223 by means of a pin and spring mechanism as illustrated, that for the contact blade of contacts 1—SU138 being designated 1—SU226. Since connection may be made to the contact studs and the contact blades in any suitable manner, the conductors by which such connections are made have, for simplicity, not been shown for the relays illustrated. A convenient manner of effecting connection to the contact blades is indicated, however, in Figure 6 by the dot-and-dash outline of a conductor 1—SU230.

Also mounted on contact arm 1—SU220 is an 60 inwardly extending shoe 1—SU231 of magnetic material. This shoe is so shaped and positioned that when armature arm 1—SU212 and contact arm 1—SU220 are each in their innermost positions as illustrated for relay 1—SU in Figure 6, the flat portion of the shoe is adjacent the free end of actuating coil 1—SU136 and in the line of magnetic flux between the end of frame 1—SU210 and the core of actuating coil 1—SU136. Preferably, a plate 1—SU232 of magnetic material is secured by two straps to the end of frame 1—SU210 so that the plate extends over the free end of actuating coil 1—SU136, the plate having a portion cut away to clear the core 1—SU213. Preferably also the end of frame 1—SU210 between the straps is extended so that it is in the

same plane as the outer, or, as viewed in Figure 5, the upper surface of plate 1—SU232. As a result of this construction, the flat portion of shoe 1—SU231 is parallel to, and only slightly displaced from, the outer surface of plate 1—SU232 when the parts are in their innermost positions (see Figure 6). When actuating coil 1—SU136 is energized, the action of the magnetic flux in the region of plate 1—SU232 results in attracting the flat portion of shoe 1—SU231 thereto, and thus, 10 in moving contact arm 1—SU220 to its innermost position and in maintaining it there, with both contacts 1—SU138 and 1—SU56 in engagement.

Contact arm 1—SU220 is of such length that its tip engages with center post 206 when the 15 parts are in their innermost positions, as illustrated for relay 1—SU in Figure 6. The center post thus serves as a mechanical stop for the inward motion of contact arm 1—SU220.

The selective up light relays (SU) for the other 20 cars are similar in construction to the one just described for car No. 1, so a detailed description of them is not made. As already mentioned, these relays are arranged radially about common center post 206, the arrangement being such that the 25 tip of the contact arm for each relay engages center post 206 when the parts of such relay are in their innermost positions, as illustrated for relay 1—SU in Figure 6.

As a result of the above construction for the 30 selective up light relays (SU), it is to be observed that each selective up light relay operates to cause engagement and disengagement of its contacts directly in accordance with energization and de-energization of its actuating coil, so long as, while 35 the actuating coil for such selective up light relay is energized, the actuating coil for no other selective up light relay is energized. Thus, under these conditions, when the actuating coil of a relay is energized, the armature arm of such relay 40 is moved to its innermost position. During this motion of the armature arm, the contact arm of such relay moves as though it was a rigid extension of the armature arm—due to the action of the contact arm spring—with the result that the 45 tip of the contact arm sweeps inwardly toward the top surface of center post 206. The contact arm of such relay is drawn to its final, innermost position, with the tip of the contact arm in engagement with center post 206 and with the contacts of such relay in engagement, by the action of the magnetic leakage flux upon the flat portion of the contact arm shoe.

When the actuating coil of such relay is de-energized, the armature arm is returned to its outward position by the action of the armature arm spring. During this motion of the armature arm, the contact arm of such relay moves as though it was a rigid extension of the armature arm— 55 due, as before, to the action of the contact arm spring—with the result that the tip of the contact arm sweeps outwardly away from center post 206 and the contacts of such relay are separated.

It is also to be observed, however, that the 60 selective up light relays (SU) are mechanically interrelated by their contact arms in such a manner that when the actuating coils for two or more relays are energized at the same time, the contacts for only one such relay engage and continue 65 in engagement, the contacts for each of the other such relays being positively prevented from engaging. This is illustrated in Figure 6, which 70 illustrates the positions of the parts when the actuating coils for the three relays 1—SU, 2—SU, and 3—SU have been, and are maintained, ener- 75

gized. As therein illustrated, only the contacts of relay 1—SU are in engagement.

In arriving at the condition illustrated in Figure 6, the actuating coil for relay 1—SU is first energized. Relay 1—SU thereupon operates in the manner previously described to bring all the parts thereof to their innermost positions. The actuating coil for relay 2—SU is then energized. Relay 2—SU thereupon operates in the manner 10 previously described, except that the tip of the contact arm thereof, as it sweeps inwardly toward the top surface of center post 206, engages with the outer surface of the tip of the contact arm of relay 1—SU, and comes to rest in engagement 15 with such outer surface, in which position the contact arm of relay 2—SU is not in its innermost position, although it is being continuously urged to such position. Instead, the contact arm of relay 2—SU is displaced from center post 206 by 20 the thickness of the tip of the contact arm of relay 1—SU. This thickness is relatively small, but is such as to prevent the engagement of contacts 2—SU56 and 2—SU138 of relay 2—SU. The actuating coil of relay 3—SU is then energized, 25 and this relay thereupon operates in the manner previously described for relay 2—SU, except that the contact arm of relay 3—SU comes to rest with its tip in engagement with the outer surface of the tip of the contact arm of relay 2—SU, in 30 which position the contact arm of relay 3—SU is displaced from center post 206 by the combined thickness of the tips of the contact arms of relays 1—SU and 2—SU. Engagement of contacts 3—SU138 and 3—SU56 of relay 3—SU is thus 35 likewise prevented.

The interdependency of the selective up light relays (SU), characterized by this mechanical "piling up" of the contact arms about a common point, is thus seen to be effective when two or 40 more relays are in energized condition at the same time. In order to eliminate any jamming of the contact arms of the relays in the event the actuating coils for two or more relays are initially energized at precisely the same instant, the contact arm tips are beveled so that the sides of the tip of each contact arm presents a knife edge to the sides of the tip of each other contact arm.

When the contact arms for two or more selective up light relays (SU) are piled up on center 50 post 206, as described, deenergization of the actuating coil for any relay not on the top of such pile results in withdrawing the contact arm of such relay from its position in such pile without disturbing the other contact arms in such pile, 55 and also results in the return of the withdrawn contact arm to its outward position as illustrated in Figures 4 and 5. Thus, referring to Figure 6, and assuming that actuating coil 1—SU136 of relay 1—SU is deenergized, armature arm spring 60 1—SU214 becomes effective and causes the return of armature arm 1—SU212 from its innermost position as illustrated in Figure 6 to its outward position as illustrated in Figures 4 and 5. During the initial portion of such return of armature 1—SU212, contact arm 1—SU220 is 65 moved substantially longitudinally away from center post 206, and thus, the tip of contact arm 1—SU220 is withdrawn from under the pile of contact arm tips without disturbing the pile. 70 During the withdrawal of contact arm 1—SU220, there is a small amount of relative motion between the armature arm and the contact arm, and a slight additional compression of contact arm spring 1—SU221. When the tip of the contact arm has cleared the pile, contact arm

spring 1—SU221 becomes effective and causes outward rotation of the contact arm relative to the armature arm until the shoulder on the rearward extension of the contact arm engages with the armature arm. At the termination of 5 the movement of the armature arm and the contact arm, the contact arm is in its outward position as illustrated in Figures 4 and 5.

It is to be observed that when a contact arm is withdrawn from under the pile, the tips of 10 each of the contact arms in the pile that were above the tip of such withdrawn contact arm move inwardly toward the center post a distance equal to the thickness of the tip of such withdrawn contact arm, the relative order of the 15 contact arms in the pile above such withdrawn contact arm remaining the same. Assuming that the contact arm withdrawn is, as with the normal operation of the system herein disclosed, the contact arm at the bottom of the pile (i. e., 20 the contact arm which is in its innermost position, and thus has its contact arm tip in engagement with the center post and has its contacts in engagement), the withdrawal of such contact arm results in inward motion of the tips of each 25 of the other contact arms in the pile a distance equal to the thickness of one contact arm tip. As an incident of this motion, the tip of the contact arm which was in engagement with the tip of the withdrawn contact arm moves inwardly 30 so that the tip of such contact arm is now in engagement with the center post, and its contacts are in engagement. As a consequence, assuming that the actuating coil of each selective up light relay (SU) is deenergized only after the 35 contact arm of such relay reaches the bottom of the pile (i. e., only after the contacts of such relay engage), the contacts of these relays are engaged successively, for one relay at a time, in the order in which the actuating coils of these 40 relays are energized.

This sequential operation of the contacts of the selective up light relays (SU) may be illustrated by referring to Figure 6. In arriving at the condition shown by that figure—wherein the 45 tips of the contact arms for relays 1—SU, 2—SU, and 3—SU are piled up on each other in the order stated, starting from the bottom of the pile—it will be recalled that the actuating coils of the relays were initially energized in the order 50 stated, and that, after initial energization, each actuating coil is maintained energized. As previously explained, only the contacts of relay 1—SU (contacts 1—SU138 and 1—SU56) are in engagement, and the contacts of relay 2—SU 55 (contacts 2—SU138 and 2—SU56) and the contacts of relay 3—SU (contacts 3—SU138 and 3—SU56) are prevented from engaging. Upon deenergization of the actuating coil of relay 1—SU, the contact arm of this relay is withdrawn 60 and returned to its outward position. The tip of the contact arm of relay 2—SU thereupon moves into engagement with center post 206, and the contacts of relay 2—SU (contacts 2— 65 SU138 and 2—SU56) are brought into engagement. The tip of the contact arm of relay 3—SU moves inwardly a distance equal to the thickness of one contact arm tip, but in its new position it is still displaced from center post 206 and its contacts are prevented from engaging. 70 Upon deenergization of the actuating coil of relay 2—SU, the contact arm of this relay is withdrawn and returned to its outward position. The tip of the contact arm of relay 3—SU thereupon moves into engagement with center post 75

206, and the contacts of relay 3—SU (contacts 3—SU138 and 3—SU56) are brought into engagement.

In summary, the construction of the selective 5 up light relays (SU) is such that a sequence is established among the relays depending on the order in which their actuating coils are energized, this sequence being maintained while the actuating coils are maintained energized. Further, it is only when a relay is at the final stage 10 of the sequence, when its contact arm is in the innermost position, that the contacts of such relay are brought into engagement. Thereafter, when this relay is removed from the sequence by 15 deenergizing its actuating coil, the relay next in the succession advances into the final stage of the sequence.

A unit comprising a group of two or more relays such as 1—SU, etc., arranged about a center post, may thus, if desired, be considered a composite structure and termed a "mechanical sequence switch".

In the diagram of Figures 2 and 3, certain other apparatus is diagrammatically illustrated 25 that is preferably described separately before undertaking a description of the operation of the complete system embodied in the diagram. In Figure 2 of the wiring diagram, there is diagrammatically illustrated a timing motor 63 connected to suitable reduction gearing 67 to drive a shaft 73. Figure 4 shows constructional details of this apparatus. The motor 63, suitably mounted upon vertical control panel 200, is arranged above the housing containing the gearing 67. If desired, the gearing may include a set 30 of spur gears 240 mounted outside of the housing so that a large range of rotational speeds for the shaft 73 may be readily obtained by the interchange of these spur gears 240 without disturbing 35 the oil-immersed gearing in the housing. The shaft 73 is provided with contact bridges 74, 94, and 103. The bridges are clamped between the jaws of arms 81, 97, and 107, respectively, from which they are insulated as by means of 40 non-conducting tubes 241. Each arm is adjustably mounted on the shaft 73 as by set screws, so that the angular spacing between the arms, and thus the contact bridges, may be set to any 45 desired amount. Figure 11 illustrates one satisfactory angular spacing.

The contact bridges are caused to rotate by the motor 63 in the direction indicated by the arrows in Figures 2 and 11. During the course 50 of this motion, starting from the position in which the contact bridges have been shown, contact bridge 103 engages with a set of stationary contacts 102 and 106; contact bridge 94 engages with a set of stationary contacts 93 and 98, and after one-half of a revolution of the shaft 73, 55 with a set of stationary contacts 95 and 98; and contact bridge 74 engages with a set of stationary contacts 75 and 82, and after one-half of a revolution of the shaft 73, with a set of stationary contacts 72 and 80. Each set of stationary contacts 60 comprises two metallic fingers of appropriate design (see Figure 11) suitably mounted upon the panel 200. As may be seen, the engagement of each contact bridge with its stationary set of contacts results in the establishment of a circuit between the stationary contacts, and since the contact bridge is normally rotated at a definite speed, as is hereinafter described, the circuit between each set of the stationary contacts is normally established at regular time intervals.

75 The wiring diagram diagrammatically illus-

trates selector brushes 1—51 and 1—132 for car No. 1, selector brushes 2—51 and 2—132 for car No. 2, selector brushes 3—51 and 3—132 for car No. 3, and selector brushes 4—51 and 4—132 for car No. 4, which travel in accordance with the 10 motions of their respective cars. This correlation of each selector brush with its corresponding car may be effected through the medium of a "floor selector" of suitable arrangement in which the selector brush may be mounted upon a travelling crosshead that moves in accordance with the motion of the car for which it is provided. When each car is at the lower dispatch floor, each selector brush for that car engages with a dispatch floor selector contact individual to that 15 car and brush, and when each car is at the upper dispatch floor, each selector brush for that car engages with a terminal floor selector contact individual to that car and brush. The selector contacts engaged by selector brushes 1—51, 2—51, 20 3—51, and 4—51 are contacts 1—52, 2—52, 3—52, and 4—52, respectively, when the respective cars are at the lower dispatch floor, and are contacts 1—42, 2—42, 3—42, and 4—42, respectively, when the respective cars are at the upper dispatch 25 floor. The selector contacts engaged by selector brushes 1—132, 2—132, 3—132, and 4—132 are contacts 1—133, 2—133, 3—133, and 4—133, respectively, when the respective cars are at the lower dispatch floor, and are contacts 1—120, 30 2—120, 3—120, and 4—120, respectively, when the respective cars are at the upper dispatch floor. These dispatch floor selector contacts may be stationarily mounted upon the floor selector at the positions corresponding to the floors for 35 which they are provided.

Floor selector brushes 1—51 and 1—132 are identical with each other and with the corresponding brushes for the other cars. Floor selector contacts 1—52 and 1—133 are identical with 40 each other and with the corresponding contacts for the other cars. A detailed description of floor selector brush 1—51 and of floor selector contact 1—52 will therefore suffice.

Floor selector brush 1—51 and floor selector 45 contact 1—52 are shown in detail in Figure 7, the brush and contact for convenience being shown in engagement, corresponding to the condition when car No. 1 is at the lower dispatch floor. Floor selector brush 1—51 is mounted 50 upon a travelling member or crosshead 1—250 and comprises a bracket 1—251 mounted thereon having a lower arm 1—252 and an upper arm 1—253. A spring piece 1—254 is secured to lower arm 1—252 and arranged to extend in the direction of upper arm 1—253. A brush 1—255 is secured to the upper end of spring piece 1—254, as by screw 1—256, brush 1—255 being of conducting material and shaped as illustrated. Screw 1—256 also secures to spring piece 1—254 60 a brush clip 1—257 having lips which overlap the spring piece and the brush to prevent rotation of the brush. Brush clip 1—257 is provided with an extension 1—258 which projects through an aperture in arm 1—253, extension 1—258 and 65 such aperture thus serving to limit the outward motion of brush 1—255.

Floor selector contact 1—52 comprises a stud 1—260 having a tungsten or other suitable tip 1—261, mounted upon a stationary floor bar 70 1—262 of the floor selector. Brush 1—255 engages with tip 1—261 as illustrated in Figure 7, when the elevator car is at the floor corresponding to that for which floor bar 1—262 is provided.

In Figure 3 of the wiring diagram there are 75

diagrammatically illustrated direction-distinguishing floor selector switches 1-131, 2-131, 3-131, and 4-131 for cars Nos. 1, 2, 3, and 4, respectively, together with floor bar lugs 1-119, 5 2-119, 3-119, and 4-119 for causing operation of the respective direction-distinguishing floor selector switches to effect the engagement of contacts 1-130, 2-130, 3-130, and 4-130 of the respective switches. In Figures 9 and 10 are 10 shown the details of direction-distinguishing floor selector switch 1-131, such details being the same for the others of such switches. In Figure 9 is also shown the floor bar lug 1-119. This is the same as the other such lugs, and is 15 shown in Figure 9 in its position relative to direction-distinguishing floor selector switch 1-131 when car No. 1 is at the upper dispatch floor.

Direction-distinguishing floor selector switch 20 1-131 is mounted upon the travelling member or crosshead 1-250 of the floor selector or equivalent device. Arm 1-270 of the switch is pivoted to a U-shaped extension 1-271 of a base member 1-272 of conducting material, the base member 25 being suitably secured to crosshead 1-250, as by the screw 1-273 and the terminal stud 1-274. Arm 1-270 is of conducting material, and has mounted at its upper end, and offset from the body of the arm, one of the contacts 1-130. 30 Arm 1-270 is normally maintained in the position illustrated as a result of the action of a spring 1-275. This spring is interposed between base member 1-272 and a lug 1-276 pivoted at its upper end to arm 1-270 and formed with a 35 lip at its lower end for engaging the edge of an aperture in arm 1-270 through which a portion of the pivoted lug projects. Such projecting portion of pivoted lug 1-276 projects sufficiently outward to engage floor bar lug 1-119, which is 40 suitably mounted on a floor selector floor bar 1-277, as switch 1-131 moves past lug 1-119. The end of arm 1-270 below the pivot for the arm engages with base member 1-272 to limit the outward motion of the arm under the action 45 of spring 1-275. The lower portion of base member 1-272 is cut away at the under side thereof, and an insulating block 1-280 is positioned in the recess thus formed and suitably secured to the base member. Block 1-280 50 extends laterally of base member 1-272, as illustrated in Figure 10, and to the lateral extension of this block is secured, as by a rivet 1-281, a contact blade 1-282 and a blade guard 1-283, each of conducting material. The lower 55 end of the blade guard is provided with a terminal screw 1-284. To the upper end of contact blade 1-282 is secured one of the contacts 1-130 and positioned so as to be engaged by the contact 1-130 on arm 1-270 when such arm is 60 moved inwardly.

Inward motion of arm 1-270, and thus the engagement of contacts 1-130, occurs when the projecting portion of pivoted lug 1-276 engages with floor bar lug 1-119 as the car moves away 65 in a downward direction from the upper dispatch floor, and thus, as floor selector switch 1-131 is moved downwardly from the position illustrated in Figure 9. Under these circumstances spring 1-275 maintains the lower lip of pivoted lug 1-276 in engagement with arm 1-270. When the car, moving in an upward direction, 70 approaches the upper dispatch floor, contacts 1-130 do not engage. This is due to the fact that, under these circumstances, as floor selector 75 switch 1-131 is moving upwardly toward the

position illustrated in Figure 9, the engagement of the projecting portion of pivoted lug 1-276 with floor bar lug 1-119, and the continued upward motion of the switch, merely results in the pivoted lug 1-276 rotating inwardly upon its 5 pivot relative to arm 1-270, against the influence of spring 1-275.

The operator's control switches 1-35, 2-35, 3-35, and 4-35 are each provided for controlling the starting of its corresponding car. For 10 simplicity, each control switch shown in Figure 2 of the diagram as provided with only one movable contact (1-36, etc.) and only one stationary contact (1-38, etc.) with which the movable contact may engage upon the throwing over of 15 the operator's control switch to start the car. Connected between the stationary contact (1-38, etc.) for each car and the conductor 30 is the actuating coil (1-S41, etc.) of the car starting 20 switch S for the corresponding car. The energization of the actuating coil of the car starting switch for a car causes, among other things, the engagement of the contacts S40 for such car (i. e., contacts 1-S40, etc.). These contacts, shown in Figure 2, cause, upon their engagement, 25 and by means of circuits, relays and other apparatus for simplicity not shown, the starting of the corresponding car.

The invention is most readily described by a 30 description of the operation of a system embodying the invention. Such a system is shown by Figures 2 and 3. It is initially assumed that the cars are in the positions and are moving in the directions as shown by Figure 1, with the result that the selector brushes 1-51, 1-132, 2-51, 35 2-132, 3-51, 3-132, 4-51, and 4-132 are in corresponding positions as shown in Figures 2 and 3. It is also assumed that the knife switches 1-50, 1-125, 2-50, 2-125, 3-50, 3-125, 4-50, and 4-125 are closed so that all four cars are 40 included in the dispatching and scheduling system; that knife switches 22, 26, 88, and 101 are closed; and that knife switch 85 is thrown to the left so that the blades 84 and 91 thereof engage the contacts 83 and 90 respectively. As a result, 45 upon the closing of the knife switches 20 and 24 to connect the dispatching and scheduling system to the plus and minus mains, the timing motor 63 is started. The circuit for the motor field 60 may be traced from the positive main, through 50 knife switch 20, wire 25, contacts K57 of the timing motor relay, timing motor field 60, wire 38, knife switch 24, to the negative main. The circuit for the motor armature 61 may be traced from the wire 25, through contacts K57 of the 55 timing motor relay, timing motor armature 61, switch arm 65 of the timing motor speed control switch 62, one of the contacts 64 of the speed control switch, a portion of resistance 66, to wire 30. The speed with which the timing motor runs is 60 dependent upon the amount of the resistance 66 that the speed control switch 62 causes to be included in the circuit just traced. For the arrangement of the resistance 66 as shown, the less resistance that is included in the motor armature circuit above traced, the faster is the speed 65 with which the motor runs.

The closing of knife switches 20 and 24 also 70 results in the energization of the actuating coil DD104 of the down dispatching relay and of the actuating coil UU108 of the up dispatching relay. The circuit for the coil DD104 may be traced from the wire 25, through wire 105, coil DD104, knife switch 88 (which has been assumed to be closed), to wire 30. The circuit for the coil 75

UU108 may be traced from the wire 28, through wire 105, coil UU108, knife switch 101 (which has been assumed to be closed), to wire 38. The consequent operation of the down dispatching relay DD causes the engagement of its contacts DD10 and the separation of its contacts DD124. The engagement of contacts DD10 prepares a circuit to the contacts D11, while the separation of contacts DD124 removes a by-pass around the contacts D122. The operation of the up dispatching relay UU causes the engagement of its contacts UU117 and the separation of its contacts UU145. The engagement of contacts UU117 prepares a circuit to the contacts U78 while the separation of contacts UU145 removes a by-pass around the contacts U143.

The closing of knife switches 20 and 24 also results in the energization of the actuating coil Z23 of the auxiliary down car holding relay and 0 of the actuating coil Y27 of the auxiliary up car holding relay. The circuit for the coil Z23 may be traced from wire 25, through wire 21, knife switch 22, coil Z23, to wire 38. The circuit for the coil Y27 may be traced from wire 25, through 5 wire 21, knife switch 26, coil Y27, to wire 38. The consequent operation of the auxiliary down car holding relay Z causes the engagement of its contacts Z109, Z113, Z117, and Z121. The operation of the auxiliary up car holding relay Y 0 causes the engagement of its contacts Y140, Y146, Y147, and Y150. As it is assumed that at this instant there are no cars at either the upper or the lower dispatch floors, the engagement of the contacts of the auxiliary down car holding relay 15 Z and of the auxiliary up car holding relay Y is of no immediate effect.

It is to be observed that, under the above conditions, the actuating coils 1—SD110, 2—SD110, 3—SD110, and 4—SD110 of the selective down light relays, and the actuating coils 1—SU138, 2—SU138, 3—SU138, and 4—SU138 are each de-energized, so that all the selective light relays are in their outward positions, as illustrated in Figure 4.

15 Assume that car No. 1 now arrives at the lower dispatch floor. Selector brushes 1—51 and 1—132 for that car thereupon engage floor selector contacts 1—52 and 1—133 respectively. The engagement of selector brush 1—132 with floor selector contact 1—133 completes a circuit for the actuating coil of the selective up light relay SU for car No. 1. This circuit may be traced from the plus main, through knife switch 20, wire 25, wire 47, knife switch 1—125, selector brush 55 1—132, floor selector contact 1—133, contacts 1—S135, actuating coil 1—SU136, wire 28, knife switch 24, to the minus main. The selective up light relay 1—SU thereupon operates. Under the conditions assumed, the selective up light relay 60 SU for each car other than car No. 1 is deenergized, with its contact arm in its outward position, so that upon energization of the actuating coil 1—SU136 of the selective up light relay for car No. 1, contact arm 1—SU220 is immediately moved to its innermost position, as illustrated 65 in Figure 6, with the tip of contact arm 1—SU220 in engagement with center post 206 and with contacts 1—SU56 and 1—SU138 in engagement.

The engagement of contacts 1—SU56 of the 70 selective up light relay, together with the engagement of selector brush 1—51 with floor selector contact 1—52, completes a circuit for three signal lights in parallel, i. e., the up hall light 1—53, up warning light 1—54, and starter's signal light 1—55.

The engagement of contacts 1—SU138 prepares a circuit for the up start light 1—137 for car No. 1. Under the assumed conditions of operation, the circuit for up start light 1—137 is incomplete at the contacts U143 and UU145, so 5 that this light is not now illuminated.

The engagement of selector brush 1—132 with floor selector contact 1—133 also completes a circuit for the actuating coil 1—A144 of the up car holding relay A, which circuit may be traced 10 from wire 47, through knife switch 1—125, selector brush 1—132, floor selector contact 1—133, contacts Y140, actuating coil 1—A144, to wire 28. Up car holding relay A thereupon operates to cause separation of its contacts 1—A33. The 15 separation of these contacts serves to prevent energization of actuating coil 1—S41 of the car starting switch for car No. 1, and thus serves to prevent the starting of car No. 1 from the lower dispatch floor.

Assume that at about this time car No. 3 arrives at the upper dispatch floor. Selector brushes 3—51 and 3—132 for that car thereupon engage floor selector contacts 3—42 and 3—120 respectively. The engagement of selector brush 3—132 with floor selector contact 3—120 completes a circuit for the actuating coil of the selective down light relay SD for car No. 3. This circuit may be traced from wire 47, knife switch 3—125, selector brush 3—132, floor selector contact 3—120, actuating coil 3—SD110, to wire 28. The selective down light relay 3—SD thereupon operates. Under the conditions assumed, the selective down light relay SD for each car other than car No. 3 is deenergized, with its contact 35 arm in its outward position, so that upon energization of the actuating coil 3—SD110 of the selective down light relay for car No. 3, the contact arm of relay 3—SD is immediately moved to its innermost position, with its contact arm tip in engagement with center post 205 and with contacts 3—SD46 and 3—SD112 in engagement.

The engagement of contacts 3—SD46 of the selective down light relay, together with the engagement of selector brush 3—51 with floor selector contact 3—42, completes a circuit for three signal lights in parallel, i. e., down hall light 3—43, down warning light 3—44, and starter's signal light 3—45.

The engagement of contacts 3—SD112 prepares a circuit for the down start light 3—111 for car No. 3. Under the assumed conditions of operation, the circuit for down start light 3—111 is incomplete at contacts D122 and DD124, so 50 that this light is not now illuminated.

The engagement of selector brush 3—132 with floor selector contact 3—120 also completes a circuit for the actuating coil 3—B116 of the down car holding relay B, which circuit may be traced from wire 47, through knife switch 3—125, selector brush 3—132, floor selector contact 3—120, contacts Z117, actuating coil 3—B116, to wire 28. Down car holding relay 3—B thereupon operates to cause separation of its contacts 3—B31. The separation of these contacts 65 serves to prevent energization of actuating coil 3—S41 of the car starting switch for car No. 3, and thus serves to prevent the starting of car No. 3 from the upper dispatch floor.

The arrival of car No. 3 at the upper dispatch 70 floor is not attended by engagement of contacts 3—130 of the direction-distinguishing floor selector switch 3—131, for, as previously explained, the pivoted lug on the switch arm, when engaged by the floor bar lug 3—119 upon the ar- 75

rival of the car at the upper dispatch floor, merely rotates inwardly relative to the switch arm.

- Assume that after the cars Nos. 1 and 3 have reached the lower and upper dispatch floors, respectively, as described above, the rotation of shaft 73 by the timing motor causes the engagement of contact bridge 103 with the stationary contacts 102 and 106, and the engagement of contact bridge 94 with the stationary contacts 93 and 96. With the illustrated setting of the arms 97 and 107 which support the contact bridges 94 and 103, the contact bridges engage their respective contacts substantially simultaneously.
- 15 The engagement of contact bridge 103 with the contacts 102 and 106 completes a circuit from wire 25, through wire 105, contact 106, bridge 103, contact 102, actuating coil U100 of the up schedule relay, knife switch 101, to wire 30. This operates the up schedule relay which engages contacts U78 and U143. The up schedule relay is of the type that mechanically latches in after being operated, as illustrated in Figure 4, so that the contacts U78 and U143 are maintained in engagement after the deenergization of actuating coil U100 when the contact bridge 103 subsequently disengages from the stationary contacts 106 and 102. The engagement of contacts U78 is of no effect at the present moment, 25 and their function will be described later.
- 30 The engagement of contacts U143 completes a circuit from wire 47, through knife switch 1-125, selector brush 1-132, floor selector contact 1-133, up start light 1-137, contacts 1-SU138, wire 148, contacts U143 to wire 28. This causes the illumination of up start light 1-137 for car No. 1.
- 35 The engagement of contacts U143 also completes a circuit from floor selector contact 1-133, 40 through contacts Y140, actuating coil 1-AA141 of the up car releasing relay, contacts 1-SU138, wire 148, contacts U143, to wire 28. This causes the operation of the up car releasing relay 1-AA. This relay, upon operation, engages contacts 45 1-AA144 and 1-AA142. The engagement of contacts 1-AA144 establishes a by-pass around contacts 1-A33, so that contacts 1-A33 are no longer effective to prevent the starting of car No. 1 from the lower dispatch floor. The engagement of contacts 1-AA142 completes a holding circuit for the actuating coil 1-AA141 of the up car releasing relay so that relay 1-AA is maintained actuated independently of contacts U143.
- 50 The engagement of contacts U143 also completes a circuit for the starter's signal light 127, traceable from wire 47, through lamp 127 and contacts U143, to wire 28. The starter's signal light 127 is thus illuminated.
- 55 The engagement of contact bridge 94 with the contacts 93 and 96 completes a circuit from wire 25, through wire 105, contact 96, bridge 94, contact 93, contact 90, blade 81 of the knife switch 85, actuating coil D87 of the down schedule relay, knife switch 88, to wire 30. The down schedule relay thereupon operates, engaging contacts D71 and D122. The down schedule relay is of the type that mechanically latches in after being operated, as illustrated in Figure 4, so that contacts D71 and D122 are maintained in engagement after the deenergization of actuating coil D87 when the contact bridge 94 subsequently disengages from the stationary contacts 93 and 96. The engagement of contacts D71 is of

no effect at the present moment, and their function will be described later.

60 The engagement of contacts D122 completes a circuit from wire 47, through knife switch 3-125, selector brush 3-132, floor selector contact 3-120, up start light 3-111, contacts 3-SD112, wire 118, contacts D122, to wire 28. This causes down start light 3-111 for car No. 3 to be illuminated.

65 The engagement of contacts D122 also completes a circuit from floor selector contact 3-120, through contacts Z117, actuating coil 3-BB114 of the down car releasing relay, contacts 3-SD112, wire 118, contacts D122, to wire 28. Down car releasing relay 3-BB is thus operated, engaging contacts 3-BB32 and 3-BB115. The engagement of contacts 3-BB32 establishes a by-pass around contacts 3-B31, so that contacts 3-B31 are no longer effective to prevent the starting of car No. 3 from the upper dispatch floor. The engagement of contacts 3-BB115 completes a holding circuit for the actuating coil 3-BB114 of the down car releasing relay so that relay 3-BB is maintained actuated independently of contacts D122.

70 The engagement of contacts D122 also completes a circuit for starter's signal light 126, traceable from wire 47, through lamp 126 and contacts D122, to wire 28. The starter's signal light 126 is thus illuminated.

75 Assume that in compliance with the signal given by the up start light 1-137, the operator of car No. 1 closes the car and hatchway doors and moves his control switch 1-35 into position to start the car. The resultant operation of starting switch 1-S effects not only the engagement of contacts 1-S40 to cause the starting of the car, but also the engagement of contacts 1-S134 and separation of contacts 1-S135. Contacts 1-S134 complete a circuit for reset coil U128 of the up schedule relay. This circuit is through switch 1-125, brush 1-132, contact 1-133, contacts 1-S134, coil U128 and contacts U143. The mechanical latch of the up schedule relay U is thus released and the relay drops back to separate its contacts U143 and U78. The purpose of the separation of contacts U78 will be explained later. The separation of contacts U143 extinguishes the starter's signal light 127, advising the starter that the operator of the car which received the up start signal has thrown his control switch to start position to start the car. The separation of contacts 1-S135 breaks the circuit for coil 1-SU138 of the selective up light relay SU for car No. 1. This relay drops back to separate its contacts 1-SU138 and 1-SU58. Contacts 1-SU138 are in the circuit for up start light 1-137 and coil 1-AA141 of the up car releasing relay, this lamp and coil being maintained energized, however, by way of contacts 1-AA142. The separation of contacts 1-SU58 breaks the circuit for up hall light 1-53, up warning light 1-54 and starter's signal light 1-55, causing these lights to be extinguished.

80 Upon the disengagement of brush 1-132 from contact 1-133 as the car leaves the first floor, the circuit for up start light 1-137, coil 1-AA141 and coil 1-AA144 is broken. The starting light is thus extinguished and up car holding relay 1-AA drops back, reengaging its contacts 1-A33 in the circuit for control switch 1-35. The dropping back of up car releasing relay 1-AA to separate its contacts 1-AA144 is delayed as by a dashpot (see Figure 4) sufficiently to insure the reen-

- agement of contacts 1-A33, thereby preventing the breaking of the feed to the control switch.
- Assume that in compliance with a signal given by down start light 3-111, the operator of car No. 3 closes the car and hatchway doors and moves his control switch 3-35 into position to start the car. The movement of the car away from the upper terminal floor results in the engagement of contacts 3-130 as floor bar 3-119 engages with the projecting portion of direction-distinguishing floor selector switch 3-131. This completes the circuit for reset coil D123 of the down schedule relay, which is from wire 47 through switch 3-125, contacts 3-130, coil D123 and contacts D122 to wire 28. As a result, the mechanical latch of the down schedule relay is released so that the relay drops back, separating its contacts D122 and D11. The purpose of the separation of contacts D11 will be explained later. The separation of contacts D122 extinguishes the starter's signal light 126, advising the starter that the operator of the car that received the down start signal has left the upper terminal floor.
- 25 As the car continues its motion from the upper terminal floor, brush 3-132 disengages contacts 3-120. This breaks the circuit for the actuating coil 3-SD110 of the selective down light relay, which drops back to separate its contacts 3-SD112 and 3-SD46. The separation of contacts 3-SD46 breaks the circuit for down hall light 3-43, down warning light 3-44, and starter's signal light 3-45, causing these lamps to be extinguished. Contacts 3-SD112 are in the circuit for down start light 3-111 and coil 3-BB114 of the down car releasing relay. However, the circuit for this lamp and coil as well as for coil 3-BB116 of the down car holding relay is broken by the disengagement of brush 3-132 from contact 3-120. Thus the down start light 3-111 is extinguished and the circuit to control switch 3-35 is reestablished through contact 3-B31, the separation of contacts 3-BB32 being delayed to insure the maintenance of a feed to the control switch.
- 50 The timing motor continues to run and thus to cause the rotation of shaft 13 in the direction indicated by the arrow. It is to be noted that with the angular spacing of the mounting arms 81, 97, and 107 illustrated in the drawings, soon after the disengagement of contact bridge 103 from stationary contacts 102 and 106 and of contact bridge 94 from stationary contacts 93 and 96, contact bridge 74 engages with stationary contacts 75 and 82. This event is of no effect under the assumed conditions of operation, however, for the circuit through these contacts terminates at the unengaged contact 86 of the knife switch 85. Subsequently, and after shaft 60 73 has rotated one-half of a revolution from the position in which bridge 94 was in engagement with contacts 93 and 96, the bridge 94 engages the stationary contacts 95 and 98. This event is also of no effect under the assumed conditions of operation, for the circuit through contacts 95 and 98 is open at switch 85. Soon after bridge 94 disengages from the contacts 95 and 98, bridge 74 engages stationary contacts 72 and 80. This event is also of no effect, for the circuit through these contacts is open at contacts U78 and contacts D71.
- 75 The next event in time is the reengagement of bridge 103 with stationary contacts 102 and 106 and of bridge 94 with stationary contacts 93 and 96 as a result of a complete revolution of the

shaft 73. Before such reengagement, however, assume that car No. 2 arrives at the lower terminal floor and that car No. 4 arrives at the upper terminal floor.

80 A sequence of operations similar to that previously described for car No. 1 transpires for car No. 2 upon its arrival at the lower terminal floor. The engagement of brush 2-132 with contact 2-133 as car No. 2 arrives at the lower terminal completes the circuit for coil 2-SU136 of the selective up light relay for car No. 2. This relay operates to engage its contacts 2-SU56, completing a circuit through brush 2-51 and stationary contact 2-52 for up hall light 2-53 at the lower terminal, up warning light 2-54 and 15 starter's signal light 2-55 for elevator No. 2. Relay 2-SU also engages contacts 2-SU138, preparing a circuit for car No. 2 up start light 2-137 and for coil 2-AA141 of car No. 2 up car releasing relay. The engagement of brush 2-132 with contact 2-133 also completes a circuit for coil 2-A144 of car No. 2 up car holding relay which operates to separate its contacts 2-A33 in circuit for control switch 2-35.

25 A sequence of operation similar to that described for car No. 3 transpires when car No. 4 arrives at the upper terminal floor. The engagement of brush 4-132 with contact 4-123 as car No. 4 arrives at the upper terminal completes the circuit for coil 4-SD110 of the selective down light relay for car No. 4. This relay operates to engage its contacts 4-SD46, completing a circuit through brush 4-51 and stationary contact 4-42 for down hall light 4-43 at the lower terminal, down warning light 4-44 35 and starter's signal light 4-45 for elevator No. 4. Relay 4-SD also engages contacts 4-SD112, preparing a circuit for car No. 4 down start light 4-111 and for coil 4-BB114 of car No. 4 down car releasing relay. The engagement of brush 4-132 with contact 4-120 also completes a circuit for coil 4-BB116 of car No. 4 down car holding relay, which operates to separate its contacts 4-B31 in the circuit for control switch 4-35.

45 When contact bridge 103 engages contacts 102 and 106, coil U100 of the up schedule relay is again energized, and its contacts U143 and U178 reengage. The reengagement of contacts U178 under the present assumed conditions of operation is, as before, of no effect. The engagement 50 of contacts U143 completes a circuit for the up start light 2-137 similar to that previously described for the up start light 1-137, and also completes the circuit for the starter's light 127. The up start light 2-137 and the starter's light 55 127 are thereupon both illuminated. Start light 2-137 is a signal to the operator of car No. 2 to leave the lower terminal while the starter's light 127 is a signal to the starter that a car at the lower terminal floor has received a signal to 60 start.

65 When the contact bridge 94 engages with the stationary contacts 93 and 96, which, with the illustrated setting of arms 97 and 107, is substantially the same time that bridge 103 engages contacts 102 and 106, actuating coil D87 of the down schedule relay is again energized and its contacts D122 and D11 reengage. The reengagement of the contacts D11 under the present assumed conditions of operation is, as before, of 70 no effect. The engagement of contacts D122 completes a circuit for the down start light 4-111 similar to that previously described for the down start light 3-111, and also completes the circuit for the starter's light 126. Down start light 75

4-111 and starter's light 126 are thereupon both illuminated, signalling the operator of car No. 4 to leave the upper terminal floor and the starter that a car at the upper terminal floor has received a signal to start.

Assume now that in compliance with the signal given by the up start light 2-137, the operator of car No. 2 starts his car upward from the lower terminal floor, and that in compliance with the down start light 4-111 the operator of car No. 4 starts his car downwardly from the upper terminal floor. In a manner similar to that described for the starting of car No. 1 from the lower terminal floor, the operation of control switch 2-35 to start position causes, through the operation of car starting switch 2-S, the reset of up schedule relay U, which extinguishes starter's signal light 127, and the energization of selective up light relay 2-SU which, upon dropping back, breaks the circuit for up holding light 2-53, up warning light 2-54 and starter's signal light 2-55. The disengagement of brush 2-132 from contact 2-133 as car No. 2 leaves the first floor breaks the circuit for up start light 2-137 and for the coils of switches 2-AA and 2-A. The departure of car No. 4 from the upper terminal floor breaks the circuit for down start light 4-111 and for the coils of switches 4-B and 4-BB, resets down schedule relay D, which extinguishes starter's signal light 126, and breaks the circuit for coil 4-SD110 of the selective down light relay, which drops back to extinguish down hall light 4-48, down warning light 4-44 and starter's signal light 4-45.

Assuming that the cycle of operations above described continues, car No. 3 is the next to arrive at the lower terminal floor and car No. 1 is the next to arrive at the upper terminal floor. Further description of operation of the system under such conditions is believed unnecessary. It is believed clear that when a car at each terminal floor is started away with reasonable promptness in compliance with the corresponding up start or down start signal given it, and that before the expiration of the normal time interval after the giving of that start signal (as determined by a complete, continuous revolution of the shaft 73) a car again arrives at each terminal floor, the start signals are given without delay at the expiration of the normal time interval. Under these conditions the start signals are given at regular intervals, and thus there is regularity in the dispatching of the cars from both terminal floors. The elevator service thus tends to be uniform, for there is normally the same number of cars on the up trip as on the down trip. This relationship among the cars may be termed as having the cars "balanced".

The above described operation of the starter's lights 45 and 55 for each car and starter's lights 126 and 127 assists the starter or other official in the complete supervision of the bank of elevators. He is informed when a dispatch signal is given by the scheduling device. He is informed all during the time a car is receiving a dispatch signal. He is also informed when the car actually leaves in response to such signal. Thus he may see whether or not the operators are starting their cars away from the terminal floors with reasonable promptness after they have received the signal to start. In the system illustrated, this supervision extends to both the lower and upper terminal floors. Utilization of the system in conjunction with the indicators that show the positions of the cars in the elevator bank enables the

starter to determine which of the cars in the bank is receiving the starting signal.

Various conditions arise in the operation of elevators which must be met in the scheduling of the elevator cars. It may happen, for example, when a car makes more than a normal number of stops during a trip, or when it is delayed for other causes, that the car has not arrived at the terminal floor by the time that it is scheduled to depart therefrom. Assume that car No. 1 has been delayed in its travel toward the lower terminal floor. The engagement of contact bridge 103 with the stationary contacts 102 and 106 before the arrival of car No. 1 at the lower terminal floor completes a circuit for the actuating coil U100 of the up schedule relay as previously described. The resulting operation of up schedule relay U causes the engagement of its contacts U18 and U143 and the mechanical latching in of the relay to maintain these contacts in engagement. The engagement of contacts U18 is of no effect at the present moment. The engagement of contacts U143 completes a circuit for starter's light 127. No other lights are lighted, however, until the car arrives at the lower terminal floor.

Upon the arrival of car No. 1 at the lower terminal floor, a circuit is completed for coil 1-SU138 of car No. 1 selective up light relay by the engagement of brush 1-132 and contact 1-133. This relay engages contacts 1-SU56, 30 completing a circuit for up hall light 1-53, up warning light 1-54 and starter's signal light 1-55 through brush 1-51 and contacts 1-52. Thus, the operator of the car is immediately advised that his car is selected to leave the lower terminal and passengers are advised that car No. 1 is available for upward travel. At the same time, the starting light 1-137 is lighted as a result of the engagement of contacts 1-SU138 of the selective up light relay, advising the car operator that his car is to leave. The up car releasing relay 1-AA is also operated, permitting the operator to start the car. This situation is maintained until, as previously described, the operator moves his control switch to start position 40 and the car leaves the lower terminal.

A similar operation occurs in the event that a car is delayed in reaching the upper terminal floor. It is believed that this will be understood from the above description, and it will not be described.

In the event that a car gets considerably behind schedule in its arrival at a terminal floor, the system acts automatically to effect a readjustment in scheduling. Assume that car No. 1 has been delayed in its travel toward the lower terminal floor while car No. 3 has arrived at the upper terminal floor substantially according to schedule, and departs therefrom promptly upon receipt of the starting signal. As a result, the 60 cycle of events with regard to the delayed car only, car No. 1, need be described. The bridging of contacts 102 and 106 before the arrival of car No. 1 at the lower terminal floor causes the operation of the up schedule relay U to latch contacts U18 and U143 in engagement as previously explained. Contact bridge 103 then disengages from contacts 102 and 106 and, with arms 81 and 82 set as illustrated, soon thereafter contact bridge 74 engages with the stationary contacts 75 and 82. This event is of no effect, as the circuit through contacts 75 and 82 is open at knife switch 85. After the disengagement of contact bridge 74 from contacts 75 and 82, substantially one-half of a revolution of timing shaft 73 en-

sues before bridge 14 engages with the contacts 12 and 80. In the event that car No. 1 has not reached the lower terminal or, if it has, the control switch 35 has not been operated to start the car therefrom when contacts 12 and 80 are bridged, the bridging of these contacts completes a circuit for energizing the actuating coil K16 of the timing motor relay. This circuit may be traced from wire 28, through contacts UU11, contacts U18, stationary contacts 80 and 12, coil K16, to wire 30. The resulting operation of the timing motor relay causes the separation of its contacts K57 in the timing motor feed. Accordingly, the timing motor stops and the timing shaft 13 ceases to revolve. The timing is thus suspended pending the departure of the car from the lower terminal floor. This suspension aids in the readjustment of the system to the excessive delaying of car No. 1, and tends to keep the cars in the desired balanced relation. When car No. 1 eventually does depart from the lower terminal floor, up schedule relay U is reset, separating its contacts U18. The separation of these contacts breaks the circuit for the actuating coil K16 of the timing motor relay, and so permits the reengagement of its normally engaged contacts K57 to cause the reenergization of timing motor 63. The timing motor thereupon resumes its operation to cause the rotation of timing shaft 13, and thus to resume the normal operations of the system.

Assume the condition reverse to that above, wherein with the arrangement of the cars and the system as has been previously described, car No. 3 has been delayed in its travel toward the upper terminal floor, while car No. 1 has arrived at the lower terminal floor substantially according to schedule and departs therefrom promptly upon receipt of the starting signal. As a result, the cycle of events with regard to the delayed car only, car No. 3, need be described. The bridging of contacts 93 and 96 before the arrival of car No. 3 at the upper terminal floor causes the operation of the down schedule relay D to latch contacts D11 and D122 in engagement as previously explained. Bridge 94 then disengages these contacts and, with arms 97 and 81 set as illustrated, soon thereafter contact bridge 14 engages with the stationary contacts 15 and 82. This event is of no effect, as before. After the disengagement of contact bridge 14 from contacts 15 and 82, substantially one-half of a revolution of timing shaft 13 ensues before bridge 14 engages with the contacts 12 and 80. During the course of this one-half of a revolution, contact bridge 94 engages with, and separates from, the contacts 85 and 98. This event is of no effect, however, for the section of circuit through these contacts is open at knife switch 85. In the event car No. 3 has not reached the upper terminal or, if it has, it has not departed therefrom when contacts 12 and 80 are bridged, the bridging of these contacts completes a circuit for coil K16 of the timing motor relay. This circuit is through contacts DD10, contacts D11 and blade 84 of knife switch 85. The timing motor relay operates to stop the timing motor and the timing is suspended pending the departure of the car from the upper terminal floor. When car No. 3 eventually does depart from the upper terminal floor, its departure results in the resetting of the down schedule relay D which breaks the circuit for the actuating coil K16 of the timing motor relay, starting the timing motor in operation again.

In the event there is a delay in the departure of cars from both terminals, the timing is suspended and is not resumed until a car departs from each terminal. This is due to the fact that the circuit for the actuating coil K16 is not broken until both contacts D11 and U18 are separated. Hence the timing motor relay K is maintained operated to keep the timing motor deenergized until the control switch 35 for the car to depart from the lower terminal is operated to start the car and until a car departs from the upper terminal.

In the event that a car is late in arriving at a terminal floor, it may be overtaken so that another car arrives at the terminal ahead of it. When this situation occurs, the overtaking car takes the place of the overtaken car, being dispatched from the terminal ahead of it, so as to minimize any delay in the scheduling of the cars. In other words, the car first to arrive at a terminal is the car first to be dispatched therefrom. This is due to the fact that the operation of the selective up light relay SU for the car first to arrive at the lower terminal interposes the tip of its contact arm SU220 on center post 206 in the path of movement of other contact arms, thereby preventing the engagement of contacts of the selective up light relay for any other car upon the energization of the coil of this relay as that car arrives at the lower terminal floor. Selective down light relay SD for the car first to arrive at the upper terminal floor interposes the tip of its contact arm on the center post 205 in the path of movement of other contact arms, thereby preventing the engagement of contacts of the selective down relay for any other car upon the energization of the coil of this relay as that car arrives at the upper terminal floor. Accordingly, when an overtaken car arrives at a terminal floor, the hall light, warning light and starter's signal light for the overtaken car are not lighted, nor does the overtaken car receive the start signal when it is given.

Assume, for example, that the arrival of car No. 1 at the lower terminal floor is delayed and that it is overtaken by car No. 2, which arrives at this terminal ahead of it. Upon the arrival of car No. 2 at the lower terminal, its selective up light relay 2-SU is operated, lighting up hall light 2-53, up warning light 2-54 and up starter's signal light 2-55, and preparing the circuit for the lighting of start light 2-131. The coil of selective relay 1-SU is also energized when delayed car No. 1 arrives at the lower terminal but, as the tip of contact arm 2-SU220 is interposed between center post 206 and the tip of contact arm 1-SU220, contacts 1-SU56 and 1-SU138 are not engaged. Thus, up hall light 1-53, up warning light 1-54 and up starter's signal light 1-55 are not lighted and the circuit is not prepared for start light 1-131. Upon the engagement of contacts U143 as a result of the operation of the timing mechanism, a circuit is completed for start signal light 2-137 but not for start signal light 1-131, thereby giving the start signal only to car No. 2. Also, only the coil of up car releasing relay AA for car No. 2 is energized so that, although the control switch 2-35 is rendered effective to start car No. 2, the circuit to control switch 1-35 to car No. 1 remains open.

Upon the attendant of car No. 2 operating his control switch 35 to start the car, up schedule relay U is reset and coil 2-SU136 of the selective up light relay for car No. 2 is deenergized. The deenergization of coil 2-SU136 results in the

withdrawal of the tip of contact arm 2—SU220, from between center post 206 and the tip of contact arm 1—SU220, permitting the latter contact arm to engage the center post and thereby close contacts 1—SU138 and 1—SU56. The engagement of contacts 1—SU56 completes a circuit for up hall light 1—53, up warning light 1—54 and up starter's signal light 1—55, thereby lighting these lights immediately. The engagement of contacts 1—SU138 prepares a circuit for start light 1—131 so that upon the next operation of up schedule relay U to engage contacts U143, as a result of operation of the timing mechanism, the start signal is given to car No. 1.

Similar operation is had at the upper terminal floor. Assume, for example, that the arrival of car No. 3 at the upper terminal is delayed and that car No. 4 arrives there ahead of it. Lights 4—43, 4—44, and 4—45 are lighted upon the arrival of car No. 4 at the upper terminal by the operation of selective down light relay 4—SD. Relay 3—SD cannot close its contacts upon the arrival of car No. 2 at the upper terminal because of the interposition of the tip of the contact arm of relay 4—SD between center post 205 and the tip of contact arm of relay 3—SD. Thus, lights 3—43, 3—44 and 3—45 are not lighted. Upon the engagement of contacts D122, the starting light 4—111 is given to car No. 4. The starting signal is not given to car No. 3 because contacts 3—SD112 are not engaged. Also, only the control switch 4—35 for car No. 4 is rendered effective. When car No. 4 leaves the upper terminal, relay D is reset and coil 4—SD110 is deenergized. The deenergization of this coil results in the withdrawal of the tip of the contact arm of relay 4—SD, permitting the engagement of the contacts of relay 3—SD. This causes the lighting of lamps 3—43, 3—44 and 3—45 and the giving of the start signal to car No. 3 upon the next operation of the timing mechanism.

More than one car may be at a terminal at a time for other reasons. For example, the delayed car may not be overtaken but another car may have caught up to it sufficiently to arrive at the terminal before the selective light relay for that terminal for the delayed car is deenergized. Or a car may arrive at a terminal at the proper time but a following car may arrive ahead of schedule. In any event, the selective relay for that terminal for a second car to arrive at that terminal cannot effect the engagement of its contacts due to the interposition of the tip of the contact arm of the selective relay for the first car to arrive between the center post and the tip of the contact arm of the selective relay for the second car to arrive. The hall lantern, warning signal light and starter's signal light for the second car will not be lighted and the second car cannot be placed in position to receive a starting signal until the deenergization of the selective relay for the car first to arrive at the terminal.

It is preferred to adjust the timing mechanism so that the interval at which cars are dispatched is such that another car does not arrive at the terminal until after a car has left. However, this interval can serve only as an average, as traffic conditions affect the operation of the cars and may cause them to be late or ahead of time. As a result, it frequently happens that two cars are at a dispatching terminal at the time a start signal is given to dispatch one of them. Traffic conditions may be such that on occasion three cars are at a dispatching terminal at the time a start signal is given, especially where a large number

of cars are operating as a group under the supervisory control of the same scheduling mechanism. When more than two cars are at a terminal at the time a start signal is given, it is important that the cars be dispatched from the terminal floor in the order in which they arrived at that floor, as the chances of their being in condition to receive the starting signal in that order is much greater. For example, car No. 1 may be the one which is about to receive the starting signal from the lower terminal, car No. 2 may be in the process of discharging its passengers at the lower terminal at that time and car No. 3 may arrive at the lower terminal just as the start signal is given to car No. 1. If car No. 3 were the one selected to be the next to receive the start signal, it would be delayed in getting away from the lower terminal because it would still have to discharge its passengers before taking on other passengers, whereas car No. 2 would have discharged its passengers and would be ready to receive passengers, thereby being in a condition to get away from the lower terminal without such delay. The schedule relays act to cause the cars to be selected to receive the starting signal in the order in which the cars arrive at the terminal, thereby minimizing any delay in dispatching the cars from the terminal. This is due to the interposition of the tips of the contact arm of each operated selective relay between the center post and the tip of the contact arm of each subsequently energized relay, thereby piling up the contact arms of the relays in such way that their contacts are made, and the cars for which they are provided are thereby selected to be the next to receive the starting signal in the order in which the cars arrived at the terminal. Furthermore, in this way only one car is made eligible to receive a starting signal at a time, so that only one car is ever dispatched at a time from the terminal floor.

The preceding descriptions are all based on the assumption that an even number of cars are in operation. In the event that it is desired to withdraw a car from the control of the system, as, for example, car No. 4, knife switches 4—50 and 4—125 are opened. As an odd number of cars are now under control of the system, knife switch 85 is thrown to the right where its blades 84 and 91 engage contacts 86 and 92 respectively. This change is made so that the odd number of cars may be dispatched from the terminals in such way as to obtain a relationship which approaches the balanced relationship obtained with an even number of cars. Under such conditions, the dispatch signal for cars at the lower terminal floor is initiated upon the engagement of contact bridge 103 with stationary contacts 102 and 106 similarly as previously described. The engagement of contact bridge 94 with contacts 93 and 96 is of no effect as the circuit partially completed thereby is open at the unengaged contact 90. During the course of a revolution of the timing shaft 73 after the engagement of bridge 103 with contacts 102 and 106, the bridge 94 engages with contacts 95 and 98. This occurs, with the illustrated setting of the arms 97 and 107, in the neighborhood of half an interval after the engagement of bridge 103 with contacts 102 and 106. The engagement of bridge 94 with contacts 95 and 98 completes a circuit through contact 92 and blade 91 of knife switch 85 for actuating coil D87 of the down schedule relay. This causes the operation of the down schedule relay and thus

the giving of the dispatch signal for a car at the upper terminal floor.

The throwing of knife switch 88 over to the right also adjusts the time-suspending function of the dispatching and scheduling system to the inclusion of an odd number of cars in the system. In the event, for example, that a car fails to leave the lower terminal floor during the interval between the engagement of bridge 103 with contacts 102 and 106 and the engagement of bridge 14 with contacts 12 and 80, the timing motor relay K operates similarly as previously described to suspend timing operations. On the other hand, in the event that a car fails to leave the upper terminal floor during the interval between the engagement of bridge 94 with contacts 95 and 98 and the engagement of bridge 74 with contacts 75 and 82, the engagement of bridge 74 with contacts 75 and 82 causes the operation of the timing motor relay K to suspend timing operations in a similar manner. The circuit for the coil of the timing motor relay K is through contacts DD10, contacts D71, blade 84, contact 86, contacts 75 and 82 and coil K16.

Accordingly, it is believed clear from the foregoing that any number of cars may be made subject to the control of the dispatching and scheduling system upon the closing of the knife switches 50 and 125 for each car to be included in the system, and the throwing of knife switch 88 to the left or right depending upon whether the total number of cars included is even or odd.

During certain times of the day, as for example, in the morning, the passenger traffic may be predominantly from the lower terminal floor up into the building. Under these circumstances it may be desirable to reduce to a minimum the period during which a car may be at the upper terminal floor waiting for the expiration of the scheduling interval after the giving of the down dispatch signal to the preceding car. In such event the starter may open knife switch 88. As a result the actuating coil DD104 of the down dispatching relay is deenergized, thereby effecting the engagement of its contacts DD124 and the separation of its contacts DD10. The engagement of contacts DD124 establishes a by-pass circuit across the contacts D122 of the down schedule relay D so that the effect is the same as if these contacts of the down schedule relay were maintained in engagement. Accordingly, as soon as a car arrives at the upper terminal floor and its selective down light relay SD operates, the circuit through its down start light 111 is complete so that the car receives the down dispatch signal immediately. The separation of contacts DD10 renders the timing suspension function inoperative for the upper terminal floor so that, with the actuating coil D87 of the down schedule relay also inoperative as a result of the opening of knife switch 88, the continued rotation of timing shaft 73 is of no effect so far as the upper terminal floor is concerned.

During certain other times of the day, as for example, in the evening, the passenger traffic may be predominantly from the upper floors of the building down to the lower terminal floor. Under these circumstances it may be desirable to reduce to a minimum the period during which a car may be at the lower terminal floor waiting for the expiration of the scheduling interval after the giving of the up dispatch signal to the preceding car. In such event the starter may open knife switch 101. This gives the same result for the lower terminal as the opening of switch 88 gives

for the upper terminal. Coil UU108 is deenergized, separating contacts UU11 and engaging contacts UU145. A by-pass circuit is established by contacts UU145 across contacts U143 of the up schedule relay U. Accordingly, as soon as a car arrives at the lower terminal floor and its selective up light relay SU operates, the circuit through its up start light 131 is complete so that the car receives the up dispatch signal immediately. The timing-suspension function for the lower terminal floor is rendered inoperative by the separation of contacts UU11 so that continued rotation of timing shaft 73 is of no effect so far as the lower terminal floor is concerned.

It is to be noted that in the event that the passenger traffic becomes extremely heavy, the starter may dispense with the scheduled interval between cars at both terminal floors by opening both knife switch 88 and knife switch 101. As a result each car receives the signal to start as soon as it arrives at a terminal floor and its selective light relay for that floor operates. In this manner the cars may be operated to give maximum service during peak traffic conditions.

In the event it is desired not to prevent the departure of the cars from the lower and upper terminal floors until the receipt by the cars of the dispatch signals, the knife switches 26 and 22 may be opened. As a result, coils Y27 and Z23 are deenergized and contacts Y140, Y146, 30 Y147, and Y150, and contacts Z109, Z113, Z111, and Z121 each separate to prevent the energization of the two actuating coils of both the up and down car holding relays for each car. If it is desired to prevent the departure of the cars from only the lower terminal floor until the receipt by the cars at that floor of the dispatch signals, only knife switch 26 may be closed so that only the up car holding relays are rendered effective. If it is desired to prevent the departure of the cars from only the upper terminal floor until the receipt by the cars at that floor of the dispatch signals, only knife switch 22 may be closed so that only the down car holding relays are rendered effective.

It is to be noted that the scheduling interval may be lengthened or shortened by the adjustment of the speed control switch 62. This switch, as previously explained, regulates the speed with which the timing motor 63 runs, and thus the speed with which the timing shaft 73 rotates.

It is also to be noted that the arms 81, 97 and 107 may be set on the timing shaft 73 at other angular relationships than those shown. For example, the arm 81 may be reset so as to increase or decrease the predetermined time after the operation of a schedule relay before the timing is suspended, in the event that no car has departed during that time. In addition, the arms 107 and 97 may be set with an appreciable angular relationship between them. The effect of this latter change is to vary the relationship between the time allowed for an up trip and the time allowed for a down trip.

It may thus be seen that the dispatching and scheduling systems as provided by this invention are capable of operating readily under numerous and various operating conditions that arise in elevator systems.

Attention is directed to the fact that when the cars are being dispatched at regular time intervals, the car eligible to receive the next dispatch signal from the lower or upper terminal floor may be ordered to start therefrom, without waiting for the expiration of the scheduling in-

5 terval, by opening the knife switch 101 for the lower terminal floor, or knife switch 88 for the upper terminal floor. This operation is due to the previously explained by-pass circuit formed around the schedule relay contacts U143 or D122.

10 It is to be understood that, if so desired, audible signals may be used in place of visual signals, or audible signals may be used in addition to visual signals. In either case, the audible signals may be single stroke or continuous stroke gongs.

15 It is also to be understood that if desired the selective relays may be deenergized and the schedule relays reset in other ways. For example, the down schedule relay D may be reset in response to operation of a control switch 35 to start a car from the upper terminal. Also, the selective down light relays may be deenergized in response to operation of the respective control switches to start the cars for which they are provided from the upper terminal. It may be desirable to provide two brushes on each selector, one for cooperating with contact 120 and the other for cooperating with contact 133, instead of one brush 132, and to render the respective feed wires to these brushes subject to direction contacts, with the brush for cooperating with contact 133 effective only when the up direction interlock contacts are closed and with the brush 30 for cooperating with contact 120 effective only when down direction interlock contacts are closed. On the other hand, the selective relays for both the upper and lower terminal floors may be deenergized by disengagement of their respective brushes 132 from contacts 133 and 120, instead of deenergizing the up schedule relays by operation of control switches 35. Also, each up schedule relay U may be reset by an arrangement similar to that shown for resetting each 40 down schedule relay D, with each switch 131 employed to complete the circuit for coil U128 closed only as the car for which it is provided leaves the lower terminal on an upward trip.

45 The construction of the mechanism comprising the selective relays may be modified and other arrangements may be employed to cause the cars to be selected to receive their starting signal in the order in which they arrive at a dispatching floor. Also, various forms of mechanism actuated in accordance with car movement may be utilized to control the lighting of the hall lights, warning lights and starters' signal lights and to control the operation of the selective relays, starting lights and schedule relays.

50 55 It is apparent that the floor selectors may be arranged so that the engagement of their brushes and contacts, for example brush 1-132 and contact 1-133 of the floor selector for car No. 1, occurs just as the car reaches the exact floor level or so that the engagement occurs in advance of the car reaching the actual floor level. This advance might be a matter of several feet, depending upon the requirements of the particular installation. It is therefore not intended that 60 the term "arrive at a floor", as used in the specification and claims, be restricted in its meaning to the car having reached the floor.

65 70 75 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In a dispatching and scheduling system for a plurality of elevator cars, not less than three, wherein each car is started from a dispatching floor upon receipt of a starting signal for that car; mechanism adapted upon each operation to cause the giving of a starting signal; means for causing said mechanism to operate at regular time intervals; and means for causing the order in which said starting signals are given to be 10 in the order in which said cars arrive at said dispatching floor, regardless of the number of said cars at said dispatching floor at the time a starting signal is given to one of such cars, and regardless of the order in which such cars arrive at said dispatching floor. 15

2. In a dispatching and scheduling system for a plurality of elevator cars, not less than three; a dispatching floor; a starting signal for each of said cars; mechanism adapted upon each operation to cause the giving of one of said starting signals; means for causing repeated operations of said mechanism; and means for causing the starting signal given in response to each operation of said mechanism to be for a car 25 positioned at the dispatching floor and for causing the order in which said starting signals are given to be in the order in which said cars arrive at said dispatching floor, regardless of their order of arrival or of the number which are at 30 said dispatching floor at the time that a starting signal is given.

3. In a dispatching and scheduling system for three or more elevator cars; a dispatching floor; a starting signal for each of said cars; switching mechanism operable to cause the giving of a starting signal to a selected one of said cars; means for causing said switching mechanism to operate at regular intervals of time; and means for selecting the car to which a starting signal 40 is given in response to each operation of said switching mechanism to be a car which has arrived at said dispatching floor, said selecting means being rendered effective, incident to the response of a car to the last starting signal given, to select the car to which to give a starting signal upon the next operation of said switching mechanism, and said selecting means acting, when two or more cars other than the one to which a starting signal has been given are at 50 the dispatching floor at the time it is rendered effective to select the next car to receive a starting signal, to select that one of such cars which was the first to arrive at said dispatching floor. 55

4. In a dispatching and scheduling system for three or more elevator cars; a dispatching floor; a starting signal for each of said cars; switching mechanism operable to cause the giving of a starting signal to a selected one of said cars; operating means for causing said switching mechanism to operate at successive predetermined intervals of time; a relay for each car; means for each car actuated in accordance with movement thereof for operating said relay for that car upon arrival of the car at said dispatching floor, said relay, upon operation, selecting that car to be the one to which a starting signal is given in response to an operation of said switching mechanism; and mechanism interlocking said relays so as to suspend the operation of a relay to select its car 70 for receipt of its starting signal until the car which arrived at said dispatching floor next ahead of that car has received its starting signal and the relay for such car released; and means for releasing each relay after the starting signal 75.

for the car for which the relay is provided has been given.

5. In a dispatching and scheduling system for three or more elevator cars; a dispatching floor; a starting signal for each of said cars; switching mechanism operable to cause the giving of a starting signal to a selected one of said cars; operating means for causing said switching mechanism normally to operate at successive predetermined intervals of time; an electromagnetic switch for each car, each switch being adapted upon energization to operate contacts to select the car for which the switch is provided to be the one to which a starting signal is given in response to an operation of said switching mechanism; means for each car for energizing said switch for that car upon arrival of the car at said dispatching floor; means associated with each switch and acting upon energization thereof to thereafter prevent the operation of said contacts of the switch for each car which arrives at the dispatching floor subsequent to the arrival thereof of the car for which that switch is provided until that switch is deenergized; and means operable incident to the starting of each car from said dispatching floor upon receipt of its starting signal for deenergizing said switch for that car.

6. In a dispatching and scheduling system for three or more elevator cars; a dispatching floor; a starting signal for each of said cars; switching mechanism operable to cause the giving of a starting signal to a selected one of said cars; operating means for causing said switching mechanism to operate at successive predetermined intervals of time; a plurality of relays, one for each car, each relay having contacts adapted, upon engagement, to select the car for which the relay is provided to be the one to which a starting signal is given in response to an operation of said switching mechanism; means for each car for causing energization of said relay for that car upon arrival of the car at said dispatching floor; mechanism for interlocking said relays so as to prevent the engagement of the contacts of each energized relay until the next previously energized relay is deenergized, thereby to prevent the giving of a starting signal to more than one car at a time and to cause the starting signals to be given in the order of arrival of the cars at the dispatching floor, regardless of their order of arrival or of the number of them which may be at the dispatching floor at any time; and means operable incident to the starting of each car from said dispatching floor upon receipt of its starting signal for deenergizing said relay for that car.

7. In a dispatching and scheduling system for three or more elevator cars; a dispatching floor; a starting signal for each of said cars; switching mechanism operable to cause the giving of a starting signal to a selected one of said cars; operating means for causing said switching mechanism normally to operate at successive predetermined intervals of time; a center post; a plurality of relays, one for each car, arranged about said center post, each relay having contacts adapted, upon engagement, to select the car for which the relay is provided to be the one to which a starting signal is given in response to an operation of said switching mechanism, and each relay having an arm adapted upon energization of the relay to interpose itself between the center post and the arm of each subsequently operated relay, thereby to prevent the

engagement of the contacts of each relay until the arms of all previously energized relays are withdrawn; means for each car actuated in accordance with movement thereof for causing energization of said relay for that car upon arrival of the car at said dispatching floor; means operable incident to the starting of each car from said dispatching floor upon receipt of its starting signal for deenergizing said relay for that car; and biasing means for each relay operable, upon deenergization of that relay to separate the contacts of the relay and also to withdraw said arm of that relay from said center post to permit the engagement of the contacts of the relay for the car next to arrive at said dispatching floor, thereby to cause the starting signals to be given in the order of arrival of the cars at the dispatching floor, regardless of their order of arrival or of the number of them which may be at the dispatching floor at any time.

8. In a dispatching and scheduling system for three or more elevator cars; a dispatching floor; a plurality of notification signals, one for each of said cars, for indicating which car is to be the next to leave said dispatching floor; means for each car for causing the giving of the notification signal for that car upon arrival of the car at said dispatching floor; and interlocking mechanism for preventing the giving of a notification signal for more than one car at a time and to cause said signals to be given in the order of arrival of the cars at the dispatching floor, regardless of their order of arrival or the number of them which are there at a time.

9. In a dispatching and scheduling system for three or more elevator cars; a dispatching floor; a plurality of notification signals, one for each of said cars, for indicating which car is to be the next to leave said dispatching floor; means for each car for causing the giving of the notification signal for that car upon arrival of the car at said dispatching floor; interlocking mechanism for preventing the giving of a notification signal for more than one car at a time and to cause said signals to be given in the order of arrival of the cars at the dispatching floor, regardless of their order of arrival or of the number of them which are there at a time; and means operable incident to the starting of each car from said dispatching floor for rendering said interlocking mechanism effective to permit the giving of a notification signal to another car.

10. In a dispatching and scheduling system for three or more elevator cars; a dispatching floor; a plurality of notification signals, one for each of said cars, for indicating which car is to be the next to leave said dispatching floor; a plurality of relays, one for each car; means for each car actuated in accordance with movement thereof for operating said relay for that car upon arrival of the car at said dispatching floor, each relay, upon operation, acting to cause the giving of the notification signal for the car for which the relay is provided; and mechanism for interlocking said relays so as to render each relay ineffective to cause the giving of the notification signal for the car for which the relay is provided, until all the relays for all cars arriving at said dispatching floor ahead of that car have been restored to unoperated condition, thereby to prevent the giving of a notification signal for more than one car at a time and to cause said signals to be given in the order of arrival of the cars at the dispatching floor, regardless of their order of arrival or of the number of them which are there.

at a time; and means operable incident to the starting of each car from said dispatching floor for restoring said relay for that car to un-operated condition.

- 5 11. In a dispatching and scheduling system for three or more elevator cars; a dispatching floor; a plurality of notification signals, one for each of said cars, for indicating which car is to be the next to leave said dispatching floor; a plurality of relays, one for each car, each relay having contacts adapted, upon engagement, to cause the giving of the notification signal for the car for which the relay is provided; means for each car actuated in accordance with movement thereof 10 for causing energization of said relay for that car upon arrival of the car at said dispatching floor; and mechanism for interlocking said relays so as to prevent the engagement of the contacts of any energized relay until all previously 15 energized relays are deenergized, thereby to prevent the giving of a notification signal for more than one car at a time and to cause said signals to be given in the order of arrival of the cars at the dispatching floor, regardless of their order 20 of arrival or of the number of them which are there at a time.

12. In a dispatching and scheduling system for three or more elevator cars; a dispatching floor; a plurality of notification signals, one for each of 30 said cars, for indicating which car is to be the next to leave said dispatching floor; means for each car for causing the giving of the notification signal for that car upon arrival of the car at said dispatching floor; interlocking mechanism 35 for preventing the giving of a notification signal for more than one car at a time and to cause said signals to be given in the order of arrival of the cars at the dispatching floor, regardless of their order of arrival or of the number of them 40 which are there at a time; a starting signal for each of said cars; switching mechanism operable at successive intervals to cause the giving of one of said starting signals; means for causing the starting signal given in response to an operation 45 of said switching mechanism to be for a car for which the notification signal is given; and means operable incident to the starting of each car from said dispatching floor upon receipt of its starting signal for rendering said 50 interlocking mechanism effective to permit the giving of a notification signal to another car.

13. In a dispatching and scheduling system for three or more elevator cars; a dispatching floor; a plurality of notification signals, one for each of 55 said cars, for indicating which car is to be the next to leave said dispatching floor; a plurality of relays, one for each car, each relay having contacts adapted, upon engagement, to cause the giving of the notification signal for the car for 60 which the relay is provided; means for each car actuated in accordance with movement thereof for causing energization of said relay for that car upon arrival of the car at said dispatching floor; mechanism for interlocking said relays so as to 65 prevent the engagement of the contacts of any energized relay until all previously energized relays are deenergized, thereby to prevent the giving of a notification signal for more than one car at a time and to cause said signals to be given 70 in the order of arrival of the cars at the dispatching floor, regardless of their order of arrival or of the number of them which are there at a time; a starting signal for each of said cars; switching mechanism operable at successive intervals to cause the giving of one of said starting 75

signals; means for causing the starting signal given in response to an operation of said switching mechanism to be for a car for which the notification signal is given; and means operable incident to the starting of each car from said dispatching floor upon receipt of its starting signal for deenergizing said relay for that car.

- 5 14. In a dispatching and scheduling system for three or more elevator cars; a dispatching floor; a starting signal for each of said cars; switching 10 mechanism operable to cause the giving of a starting signal to a selected one of said cars; operating means for causing said switching mechanism normally to operate at successive predetermined intervals of time; a notification signal for 15 each of said cars; a plurality of relays, one for each car, each relay having contacts adapted, upon engagement, to select the car for which the relay is provided to be the one to which a starting signal is given in response to an operation of 20 said switching mechanism, and having additional contacts adapted, upon engagement, to cause the giving of the notification signal for the car selected to indicate that such car is to be the next to leave the dispatching floor; means for each 25 car for causing energization of said relay for that car upon arrival of the car at said dispatching floor; mechanism for interlocking said relays so as to prevent the engagement of the contacts of each energized relay until all previously energized 30 relays are deenergized, thereby to prevent the selection for receipt of a starting signal of and the giving of a notification signal to more than one car at a time and to cause the notification signals to be given and the cars selected for receipt of their starting signals in the order of arrival of the cars at the dispatching floor, regardless of their order of arrival or of the number of them which may be at the dispatching floor at 35 any time; and means operable incident to the starting of each car from said dispatching floor upon receipt of its starting signal for deenergizing said relay for that car.

- 45 15. In a dispatching and scheduling system for three or more elevator cars; a dispatching floor; a starting signal for each of said cars; switching 50 mechanism operable to cause the giving of a starting signal to a selected one of said cars; operating means for causing said switching mechanism normally to operate at successive predetermined intervals of time; a notification signal for 55 each of said cars; a center post; a plurality of relays, one for each car, arranged about said center post, each relay having contacts adapted, upon engagement, to select the car for which the relay is provided to be the one to which a starting signal is given in response to an operation of said switching mechanism, and having additional contacts adapted, upon engagement, to cause the giving of the notification signal for the car for 60 which the relay is provided to indicate that such car is to be the next to leave the dispatching floor, and each relay having an arm adapted upon energization of the relay to interpose itself between the center post and the arm of each subsequently operated relay, thereby permitting engagement of the contacts of the relay for which it is provided when no other arm is between it and the post but preventing the engagement of the contacts of each subsequently energized relay 65 until withdrawn; means for each car actuated in accordance with movement thereof for causing energization of said relay for that car upon arrival of the car at said dispatching floor; means 70 operable incident to the starting of each car from 75

5 said dispatching floor upon receipt of its starting signal for deenergizing said relay for that car; and biasing means for each relay operable, upon deenergization of that relay, to separate the contacts of the relay and also to withdraw said arm of that relay from said center post to permit the engagement of the contacts of the relay for the car next to arrive at said dispatching floor.

thereby to cause the notification signals to be given and the cars selected for receipt of their starting signals in the order of arrival of the cars at the dispatching floor, regardless of their order of arrival or of the number of them which may 5 be at the dispatching floor at any time.

CHARLES HARVEY LEVY, JR.
